UNITED STATES PATENT OFFICE.

GROSVENOR N. ALLEN, OF ONEIDA, NEW YORK.

DESIGN FOR A DISH OR SIMILAR ARTICLE.

Application filed March 26, 1927. Serial No. 21,352. Term of patent 14 years.

To all whom it may concern:

Be it known that I, GROSVENOR N. ALLEN, a citizen of the United States, residing at Oneida, county of Madison, State of New York, have invented a new, original, and ornamental Design for a Dish or Similar Article, fully described and represented in the following specification and the accompanying drawing, forming a part of the same, in which Fig. 1 is a plan view and Fig. 2 a section thereof on the line 2—2, showing a tray embodying the essential feature of the design, namely, the ornamental matter near the ends of the tray.

I claim:

The ornamental design for a dish or similar article as shown and described.

In testimony whereof I have hereunto set my hand.

GROSVENOR N. ALLEN.
